CLAIM

I claim the ornamental design for instrument for ocular surgery, as shown and described.

DESCRIPTION

FIG. 1 is an upper perspective view of the instrument for ocular surgery showing my design.

FIG. 2 is a side view;

FIG. 3 is an opposite side view thereof;

FIG. 4 is a front elevation view thereof;

FIG. 5 is a back view thereof;

FIG. 6 is a top plan view thereof; and,

FIG. 7 is a bottom view thereof.

The instrument is made of translucent material, such that the broken lines in FIGS. 1-7 are presented to show visible mounted end of a tip of the instrument.
